Term of patent 14 years

(Cl. D34—5)

Fig. 2.

Fig. 1.

Fig. 2.

Fig. 3.

Fig. 1 is a rear perspective view of a combined score table and score projector or similar article showing my new design;

Fig. 2 is a front perspective view thereof;

Fig. 3 is a side elevational view thereof, the upstanding portion illustrated in broken lines in Figs. 1 and 2 being omitted; and

Fig. 4 is a top plan view, as shown in Fig. 3.

The dominant features of the design are shown in full lines.

Portions of the drawing figures are diagonally lined to indicate transparency.

I claim:

The ornamental design for a combined score table and score projector or similar article, as shown and described.
